DESK TRAY

Milton Revzin, 727 Delaware Ave., Youngstown, Ohio

Filed Oct. 14, 1964, Ser. No. 82,166

Term of patent 7 years

(Cl. D74—9)

The figure on the drawing is a perspective view of a desk tray, showing my new design:

The other side and end of the desk tray are of the same configuration as the respective side and end illustrated. The bottom between the parallel legs is substantially plain.

I claim:

The ornamental design for a desk tray, as shown and described.
